UNITED STATES PATENT OFFICE

ARTHUR PATEMAN, OF LEICESTER, ENGLAND, ASSIGNOR TO IMPERIAL TYPEWRITER COMPANY LIMITED, OF LONDON, ENGLAND, A BRITISH COMPANY

TYPEWRITER

Application filed May 17, 1932, Serial No. 611,894, and in Great Britain September 18, 1931.

This invention is for improvements in or relating to typewriters and is concerned with typewriters of the kind comprising a framework housing the type mechanism, including the type bars and operating levers, which framework has a top member at least partially covering the type mechanism. Generally this top member carries the platen and the ribbon spools.

10 One object of the present invention is to render the type mechanism within the framework more readily accessible, and the invention comprises a typewriter of the kind described, characterized in that the top member of the framework is readily movable away from the main part of the frame, for example, is hinged thereto, in order to render the type mechanism easily accessible, for example, for its removal from the framework.

15 20

In one form of the typewriter according to this invention the top member of the framework is hinged to the main part of the frame about an axis parallel to that of the platen and at the rear side of the framework and spring-operated latches are preferably provided for retaining the top member of the frame in the normal closed position. In a preferred construction these latches comprise levers pivoted on the main part of the framework and formed with cam slots engaging studs carried by the top member. By reason of the cammed form of the slots engaging the studs the top member is drawn tightly down on the main part of the frame by the closing of the latches. Conveniently the studs are eccentrically mounted and are provided with means for adjustment in order to ensure that the latches shall firmly hold the top member in the closed position by reason of the cam slots of the latch levers.

The invention will now be further described by way of example with reference to the accompanying drawings illustrating one form of typewriter according to this invention.

In the accompanying drawings:

Figure 1 is a side elevation with the top member in the closed position;

Figure 2 is an opposite side elevation with the top member in the open position;

Figure 3 is a detail view of one hinge for the top member of the framework;

Figure 4 is a view at right-angles to Figure 3;

Figure 5 is a detail view of the spring-closed latch in the closed position;

Figure 6 is a view at right-angles to Figure 5;

Figure 7 is a view similar to Figure 5 of the latch in the extended position; and

Figure 8 is a detail of a holding down stud for the type mechanism.

In the several figures of the drawings like reference numerals serve to indicate like parts.

The main frame of the typewriter indicated at 10 carries brackets 11 one on each side of the frame upon which brackets the type mechanism indicated in outline at 12 is supported by means of studs 13.

The top member 14 of the framework carrying the platen carriage indicated at 15 and spools 16 is hinged at the rear side to the main part 10 of the framework by means of two hinges 17 one on each side of the framework.

The hinges 17, as shown in detail in Figures 3 and 4, each consists of a lug 19 depending from the top member of the frame and located in a recess 20 provided in the rear wall of the main part 10 of the framework by means of a pivot pin 21 screw-threaded in the lug and having a bearing in the main frame. The depending lug 19 is formed with an extension 22 which abuts against a stop 23 provided on the main frame 10 in order to limit the opening movement of the top member 14.

The top member 14 of the framework is retained in the normally closed position by means of spring-operated latches 18 one on each side of the framework near the front. Referring more particularly to Figures 5, 6 and 7 of the drawings, the top member 14 of the framework is provided with depending lugs 25 each carrying a transverse screw-threaded stud 26, this stud having a cylindrical head 27 and being secured by nuts 28.

The latches each comprise a lever 29 pivoted by means of a stud 30 on the main part 10 of the framework and formed with an open-ended cam slot 31. The lever 29 is urged to the closed position of the latch by means of a tension spring 32, and is provided with an operating knob 33 projecting through a slot 34 in the main framework to the outer side thereof. A stop 39 serves to limit the range of movement of the lever.

In the open position of the top member the lever 29 assumes an approximately vertical position bearing against the stop 39 under the action of the spring 32. The end of the lever is formed with a striking surface 36 and in the closing movement of the top member the head 27 of the stud 26 bears upon this surface and deflects the lever against the action of the spring 32 until the stud head is opposite the open end of the slot 31 as shown in Figure 7. The lever 29 is then moved by the spring 32 and the slot 31 passes over the stud to hold the top member of the framework in the closed position.

25. The slot 31 in the lever 29 is so constructed that the radial dimension from the pivot 21 of the lever decreases slightly from the open end in order to exert a wedging action on the stud head 27 to hold the top member firmly 30 in the closed position. Furthermore, in order to ensure close fitting of the latch, the head 27 of the stud 26 is slightly eccentric and the position of the head may thus be adjusted by rotation of the stud.

35. In order to retain the type mechanism firmly in position when the top member is closed, the latter is provided with two studs 37 one on each side of the frame, which studs, in the closed position of the top member, bear upon 40 the type unit. Each of these studs is carried in a boss 40 formed with the top member of the framework. Each stud 37 (see Figure 8) is provided with a collar 41 and a compression spring 42 between the collar and a 45 web 43 in the boss, so that the stud is spring-pressed against the type mechanism. The stud is also provided with a retaining collar 44.

50. By means of the hinged construction, the top member of the framework is readily moved, on releasing the latches by means of the operating knobs 33, from the normally closed position, as indicated in Figure 1, to the open position, as shown in Figure 2, to 55 render the type mechanism easily accessible. The type mechanism 12 can also be removed as a unit from its normal position in the framework without any difficulty.

60. It is to be understood that the invention is not restricted to the particular construction hereinbefore described with reference to the accompanying drawings. For example, the invention may be applied to typewriters as described in specification No. 257,660 in 65 which the type mechanism is supported on

runners within the framework and is movable forwardly on these runners to permit the type mechanism to be withdrawn from the front of the machine. The removal of the type mechanism in this construction requires some-
70 what adept handling, in order to avoid fouling of parts of the type mechanism with the framework. By providing a readily movable top member of framework according to the present invention, the type mechanism may be removed from the machine with the utmost ease.

75. I claim:—

In a typewriter the combination of a frame-
work, bearing members within said frame-
work, type mechanism removably mounted
within said framework and supported on said
bearing members, a top member at least par-
tially covering said type mechanism, a hinge
connection between said top member and said
framework, locking means for retaining the
top member in the closed position and bearing
members on said top member and en-
gaging the type mechanism in the closed posi-
tion of the top member to retain the type
mechanism firmly in place.

80. In testimony whereof I affix my signature.
ARTHUR PATEMAN.
